UNITED STATES PATENT OFFICE.

EDWARD M. CARROLL, OF SANFORD, FLORIDA.

MAIN ROD FOR LOCOMOTIVES.

Application filed October 6, 1924. Serial No. 741,917.

To all whom it may concern:

Be it known that I, EDWARD M. CARROLL, a citizen of the United States of America, residing at Sanford, in the county of Seminole and State of Florida, have invented 5 certain new and useful Improvements in Main Rods for Locomotives, of which the following is a specification.

My invention relates to new and useful 10 improvements in main rods for locomotives, and especially to the rear end thereof.

One of the objects of the invention is to so construct the rear end of the rod that the bushing may be easily changed, when desired, with a minimum amount of labor, or, in case of a breakdown, the rod can be easily and quickly chained up to clear the pin without necessitating the removal of the rod or crank arm, the casing and bushing 20 being left on the pin acting as a spacer block to keep the side rod in position when the engine is being run to the shop.

Still another object of the present invention is to provide a main rod having its one 25 end so constructed that the casing which encloses the brass bushing may be quickly and readily adjusted with regard to the pin so that the rod will not pound or knock when the bushing is held in its proper position.

Still another object of the invention is to so construct the rear end of the rod so that the same will accommodate the bushing, as shown in the patent granted to me on February 6, 1917, No. 1,214,509.

Still another object of the invention is to so construct the rear end of the rod so that the bushing may be easily renewed, easily centered, tightly held in place, and capable of a fine adjustment, and, when found necessary to lengthen or shorten the rod, the same effect may be obtained by planing off one side of the casing and building up on the other side, rather than removing the whole rod and subjecting it to heat in the usual 40 manner.

With these and other objects in view, the invention consists in certain new and novel arrangements and combination of parts as will be hereinafter more fully described and 45 pointed out in the claims.

Referring now to the drawings, showing a preferred embodiment of the invention,

Fig. 1 is a fragmentary view of the rod showing the rear end thereof with the several parts in position.

Fig. 2 is a fragmentary sectional view of Fig. 1.

Fig. 3 is a vertical sectional view of Fig. 1.

Fig. 4 is a perspective view of the tapered rod wedge and spacer block, and 60

Fig. 5 is a sectional view showing the spacer block held in position.

Referring now more particularly to the drawings, there is shown a fragmentary portion of the main rod 1, with the rear end 2 65 having the jaws 3 in which there is designed to be placed a box-like casing 4 which is, in turn, provided with the outstanding flanges 5 on the opposite side of the casing so as to overlap the jaws, as may 70 be clearly seen in Figs. 1 and 2. This casing is provided with the raised rim 6 on its opposite faces, while extending through the casing is the aperture 7 for the reception of the brass bushing 8 which should be tightly 75 driven within the aperture. The bushing may be of any desired thickness, and I have found that one may be used as thin as three-eighths of an inch.

Extending annularly and centrally of the 80 casing about the aperture 7 is the oil or groove ring 9, while within the top of the casing is a passageway 10 designed to register with the ring 9 and with the passageway 11 within the head of the rod in which will be placed a grease cup 12. The brass bushing 8 is provided with a plurality of small holes 13 which in turn register with the oil ring or groove 9 so that a plentiful supply 85 of oil or grease may be supplied at all times 90 to the brass bushing and pin (not shown).

It is to be further noted that the casing 4 has one of its side walls beveled as at 14 so that a wedge member 15 may be placed 95 within the jaws 3 and one portion thereof extend between one jaw and the side 14 of the casing, while the lower portion or base 16 of the wedge member contacts throughout with the lower face of the casing.

It is also to be noted that this wedge member 15 and its base portion 16 are of substantially the same width as the thickness of the casing so that a maximum amount of contact may be had between the wedge member and the casing. This is desirable as it 105 prevents any lateral or shifting movement of the casing within the jaws, and tightly holds the casing up in position.

In the left-hand jaw 3, there will be noticed a rectangular opening 17 and a similar 110

but larger opening 18 in the opposite jaw. The openings are provided for the reception of the tapered rod 19 as shown in the several views, which rod in turn bears against the 5 base 16 of the wedge 15 and the walls of openings and by having one end of the rod 19 threaded, as at 20, and by providing the cup 21, the nut 22, when pulled up will tightly force the wedge, casing and bushing 10 into place. To prevent the jaws from being pulled together too tightly, a spacer block 23 is shown through which extends the opening 24, so that a bolt 25 may be passed therethrough and through the openings 26 in the 15 opposite jaws, the bolt securely holding the spacer block in position.

From the foregoing it will be seen that the rear end of the rod is extremely simple in construction; that the bushing may be 20 quickly and easily removed, and that the entire arrangement consists of but relatively few parts, to wit, the casing and bushing, the wedge member, the tapered rod and spacer block. Furthermore, the adjustment 25 of the casing can be quickly attended to so that the bushing and casing will always be properly centered and so that the other advantages mentioned in the forepart of the specification may be accomplished.

30 I am aware that it is old to use jibs and keys and wedges of different forms and construction, and I do not claim my invention broadly as such, but what I do claim and desire to secure by Letters Patent is:—

35 1. A main rod for a locomotive the rear end of which is provided with two jaws, a casing slidably fitting within the jaws and said casing provided with outstanding flanges to hold the casing against lateral movement, one wall of the casing being beveled, and a wedge member having a portion 40 cooperating with the beveled wall and one of the jaws, and a further portion of the wedge member extending across the bottom wall of the casing, a tapered rod passing through the opposite jaws and adapted to contact with the base of the wedge member to thereby tightly jam the casing in place, a spacer block held between said jaws, said 45 casing being provided with a central aperture and a brass bushing fitting within said aperture and said casing, bushing and upper portion of the end of the rod provided with passageways to supply grease to said bushing.

50 2. A main rod for a locomotive, the rear end of which is provided with two jaws, a rectangular casing slidably fitting within said jaws, and said casing having outwardly 55 extending flanges on its opposite faces to

overlap the jaws, said casing provided with a central aperture and a bushing fitting within said aperture, the wall of the aperture provided with a groove and the said bushing provided with a plurality of holes 60 registering with said groove, the upper portion of the rear end of the rod provided with an aperture registering with a groove in the casing to provide oil to said bushing, one wall of the casing being beveled and a wedge 65 member comprising a base the width of which is substantially the thickness of the casing and the other portion of the wedge member cooperating with the beveled wall of one of the jaws, tapered means passing 70 through said jaws for contacting with the face of the wedge member and tightly forcing the casing in position within the jaws, and a spacer block removably held between 75 said jaws.

3. A main rod for a locomotive comprising jaws at the rear and thereof, a casing slidably fitting within said jaws and means cooperating with the jaw and two walls of the casing for holding the casing in position, tapered means cooperating with said last mentioned means for holding the several parts in their forced position, a spacer block between the jaws and means for holding the spacer block in position, the said 80 casing provided with a central aperture, a bushing tightly fitting within said aperture, and the rear end of the rod, casing and bushing being provided with the registering 85 passageways and openings for supplying 90 grease to the bushing.

4. A main rod for a locomotive, the rear end of which is provided with jaws, a casing slidably movable within said jaws, a wedge member fitting below said casing and one 100 wall of the casing being beveled to cooperate with said wedge member, a tapered rod passing through said jaws and adapted to contact with the base of the wedge member, and means for pulling up on the tapered rod to thereby force the casing through the medium of the wedge tightly in position, a spacer block between said jaws to limit the compression on said jaws, said casing provided with an aperture, a bushing within 105 the aperture, and a groove located in said casing extending about the aperture, the bushing provided with a plurality of openings registering with the groove, and the casing and rear end of the rod provided 110 with passageways to permit grease to be forced into the bushing.

In testimony whereof I affix my signature.

EDWARD M. CARROLL.
